COASTAL AND LIKE DEFENSE UNIT

William Arthur Phillips, London, England

Application August 15, 1941, Serial No. 407,075
In Great Britain August 23, 1940

2 Claims. (Cl. 114—4)

This invention relates to coastal and like defense units having the form of floating structures or hulls which are capable of being grounded, anchored or moored off the shore, or in estuaries or rivers for example, and which are adapted to be equipped for defense against enemy attack or for auxiliary purposes. Such units may be of various kinds according to the service they are required to perform. Thus for example a defense unit proper will comprise a floating hull having accommodation for a crew and provided with suitable armament, but units constructed on the same general principles and moreover of standard hull form may be adapted and equipped for use as store vessels, searchlight posts, wireless stations, anchorages for barrage balloons and other purposes. Large numbers of the units may be grouped in appropriate surroundings at convenient distances apart and may be disposed to afford the most effective co-operation between the units which may be adapted and equipped for different purposes. It will readily be understood, however, that the units have a wide variety of uses particularly for war purposes but in many instances isolated units may be effectively employed. The hulls may also be adapted for use as floating residences, as hotels and for other peaceful purposes.

For example, they may be employed as lightships or other aids to navigation.

It is an object of the invention to provide a form of floating unit or hull for the purposes indicated which is particularly suited, in respect of the characteristics of seaworthiness and steadiness to the conditions of service required.

Another object of the invention is to provide a defense unit of the character described which will afford a high degree of steadiness and controlled action in a sea-way.

According to the invention, the unit comprises a buoyant structure or hull having a relatively great draft or depth as compared with conventional hull form, or as compared with the freeboard, and the vertical section being of interrupted or stepped form including an upper part lying at the water plane joined to one or more lower parts of smaller diameter by a shouldered portion. Preferably the unit comprises two main parts, the upper part being of a relatively large area in plan (in relation to its depth) and the lower part being of smaller diameter with a definite step or shoulder connecting the parts, which step may be either flat or inclined. The relative proportions of these parts are chosen to give a suitable initial stability combined with a reason-

able rolling period. It is well understood that ordinarily a shallow draft vessel having a relatively large area at the water plane may have initial stability and a short rolling period, that is to say such a vessel will be stiff and jerky in action in a sea-way. Conversely a vessel having a deeper draft and a relatively small water plane area will generally have a long rolling period and easy movement in a sea-way. The form of unit described above partakes of both the characteristics referred to and thus provides the best conditions for the service which the unit is required to perform, namely a reasonably steady gun platform, a comparatively high initial stability, and a steady roll.

It is preferred that the unit should be substantially symmetrical in plan although some deviation in one or other of the different parts of the units may be made, e. g., such may be slightly elongated, particularly the top section. In the preferred construction the curved sides and generally tapered conical section together with the spheroidal or dome-shaped (otherwise pear-shaped) bottom are best adapted to resist severe shocks by dispersing the forces which may be set up due to explosions below the water in the near vicinity. Having inherent resistance to collapse, the form takes full advantage of the properties of concrete, necessitating the minimum amount of steel reinforcement to take tensile strains. According to a further feature of the invention the step or shoulder which connects the parts of different diameter is in the form of an inverted truncated cone of large angle with apex downwards and offers considerable resistance to rolling action. In some cases a circular keel may be formed below the bottom proper, offering resistance to rolling and affording increased steadiness.

According to a further feature of the invention, the lower part of the unit, i. e., that having the smaller diameter, is also in the form of a truncated cone having a relatively small cone angle. This permits a more equal distribution of pressure such as may be caused by a bomb explosion and affords greater freedom of movement in an upward direction. In order to meet excessive strains in a vertical direction resulting from such an explosion the floor or deck is preferably shaped and strengthened to distribute the strain as evenly as possible.

According to a further feature of the invention, the upper part of the unit is of substantially uniform cross section and is preferably polygonal for greater ease in construction. The lower section may also be polygonal in plan, although cir-

cular sections in either or both parts may be adopted if desired. Moreover, the lower part may be substantially cylindrical or prismatic.

According to a further feature of the invention there may be provided stiffening webs extending between the upper and lower parts of the structure external to the connecting shoulder. These webs will be in general of triangular form and they may be so constructed as to act as fins offering resistance to any tendency to rotation of the unit about its vertical axis and also resistance to rolling.

In the preferred mode of constructing the units, reinforced concrete is used, but other materials may be employed if desired. Provision may be made for an outer covering of resilient and waterproof material to reduce the effect of sudden shocks, as for example such as may be caused by a bomb exploding in the water nearby.

The interior of the structure will generally be provided with decks and suitably equipped for the service required. Deck lights may be fitted and these may be removable if desired.

An example of the preferred mode of carrying the invention into effect will now be described with reference to the accompanying drawings, in which:

Figure 1 is a vertical section through a floating defense unit according to the invention;

Figure 2 is a plan view of the unit; and

Figure 3 is a partial sectional view showing the arrangement of the strengthening webs.

In carrying the invention into effect according to one convenient mode, as applied by way of example to a floating unit for accommodating a crew of about six to twelve men, there is provided a reinforced concrete hull, having an upper part 1 which is substantially cylindrical and of constant cross-section, and a lower part 2 in the form of an inverted truncated cone having a small angle with the vertical and with the apex downwards. The depths of these two parts may be, for convenience, substantially equal and they are joined by a truncated conical shoulder or step portion 3 preferably lying at about the level of the lower deck. The diameter of the upper portion may be, for example, about twenty-two feet and the total depth of the unit about twenty feet. Two decks are provided, an upper deck 4 with about three feet freeboard (i. e., about six feet to top of rail or solid bulwark) and a lower deck 5 at about the level of the lower part of the connecting shoulder 3. These decks are of reinforced concrete and are formed integral with the hull proper represented by the portions 1 and 2. The arrangement may be varied as desired, subject to providing sufficient freeboard according to the angle of inclination considered necessary. Each deck has a large central aperture to enable the stores and equipment to be introduced. Thus in the top deck 4 there is provided an aperture surrounded by an annular wall 6 which supports the removable deck plating or gun platform 7. This also provides support for the gun 8. A platform 9 surrounds the annular wall 6. This may alternatively be formed by an extension of the plating 7. Ventilators 10 are provided at convenient points in the upper deck, which is surrounded by the bulwarks 11.

The lower deck is fitted up as quarters for the crew and access thereto is obtained by way of a hatch 12 which is provided with a hood 12a. A portable davit 13 is provided for lowering stores and a ladder 14 leads to the lower deck.

The lower deck 5 has a large central aperture which is covered by a removable water-tight wooden floor 15. The space is subdivided by partitions 16 and fitted with bunks 17.

5 Beneath the lower deck 5 is a stores compartment having a floor 18. The bottom 20 of the hull is provided with an upstanding annular wall 21 concentric with the hull which provides a support for the floor 18 and also for a water tank 19. Other stores including ammunition may be disposed in this lower compartment.

In order to strengthen the hull structure a number of stiffening webs or gussets may be provided. Strengthening webs 22 are provided under the upper deck 4 and are continued downwardly along the walls of the lower deck. Similar webs 23 are provided beneath the lower deck. Additional stiffening webs 24 are provided in the angle formed by the connecting shoulder, i. e., 15 under the upper part of the hull structure. These webs extend in vertical planes and are roughly triangular in shape so that the main reinforcement may be conveniently carried through. They are suitably reinforced, the reinforcement connecting with that of the main hull structure. The cross-section of the webs is preferably slightly tapering to facilitate the removal of the shuttering. Any desired number of webs may be provided and they may also serve as steadyng fins and for checking rotational movement of the unit about the vertical axis. Webs 25 are 20 also provided external to the bottom 20 of the hull which slopes towards the centre.

The hull may be provided with fender members 26 and riding lights 27. The load water line is indicated at 28 and the light water line at 28a.

It will be understood that the details of shape given above may be widely varied without departing from the general principles previously defined. Thus while the hull structure is preferably circular or approximately circular in plane, this may be modified by making certain or any of the parts of an oval or other shape in plan. Thus for example the upper hull part may be 45 oval, or polygonal approximating to an oval form, and the remaining parts circular or prismatic, and various combinations may be adopted. In general, however, the plan of the structure will be symmetrical or nearly so about a vertical axis and the draft or depth will be relatively greater than the horizontal dimension as compared with the conventional boat shape which is elongated in the horizontal direction.

The invention may be applied with advantage 50 to the defense units described in the specification of British patent application No. 10,822 of 1940 and may embody all the variations suggested therein. While the preferred material is reinforced concrete it will be appreciated that the advantages of the present invention may be obtained with other materials, the choice of which will depend upon the supplies available. Means may readily be provided for varying the metacentric height to suit different conditions and 55 requirements, and such means may conveniently comprise chambers adapted to be filled and emptied as desired. Air compression plant may be provided for this purpose and it is preferred that such chambers should be situated near the bottom of the hull.

I claim:

1. A floating structure of the type described having a hull composed of an upper part and a lower part of reduced diameter joined by a shoudered portion, vertical uprights in the bottom of

the lower part, a deck supported thereon, an intermediate deck arranged approximately at the top of the lower part having a central opening, a reinforcement about the central opening, a removable cover for said opening, said deck dividing the interior of the hull into upper and lower compartments, an upper deck near the top of the upper part of the hull provided with a central opening, a reinforcing flange about the opening, a gun mounting supported on the reinforcing flange and acting as a closure for the opening, a hatch provided in the upper deck for establish-

ing means for communication with the upper compartment, the upper compartment being adapted to serve as living quarters and the lower compartment as space for storing supplies.

5 2. A floating structure as claimed in claim 1, in which reinforcing ribs are provided on the inner surfaces of the side walls of the upper and lower parts of the hull and extend beneath the decks to the flanges about the openings in the 10 adjacent decks.

WILLIAM ARTHUR PHILLIPS.
